UNITED STATES PATENT OFFICE

FRANK J. ABEL, OF NEW YORK, N. Y., ASSIGNOR TO SUN RISE LAMP MFG. CO., INC., A CORPORATION OF NEW YORK

DESIGN FOR A CANDLESTICK OR ARTICLE OF ANALOGOUS NATURE

Application filed February 6, 1930. Serial No. 34,442. Term of patent 3½ years.

To all whom it may concern:

Be it known that I, FRANK J. ABEL, a citizen of the United States of America, and a resident of the city of New York, in the county of Bronx and State of New York, have invented a new, original, and ornamental Design for Candlesticks or Articles of Analogous Nature, of which the following is a specification, reference being had to the accompanying drawing, forming a part hereof.

Figure 1 is a side elevational view of the candlestick or article of analogous nature showing my new design; and

I claim:

The ornamental design for a candlestick or article of analogous nature substantially as shown.

FRANK J. ABEL.
